UNITED STATES PATENT OFFICE.

CARL ALFRED SVENSSON AND THEODOR COLLIN, OF FALUN, SWEDEN.

BOGIE FOR RAILWAY CARS AND THE LIKE.

Application filed July 16, 1926, Serial No. 122,748, and in Sweden July 20, 1925.

This invention relates to improvements in 5 boggies for railway cars and the like, in which the load is transmitted by springs to a beam or the like supported by the journal boxes, the springs being placed in vertical recesses in the beams and compressible by means of a bolt or the like.

The object of the invention is to secure the 10 parts from being damaged and to improve 15 designs of the said kind generally.

The invention consists, chiefly, in the bottoms of the recesses being provided with a 20 projecting sleeve adapted to receive the bolt head and having such a length as to entirely 25 embrace the bolt head in every position of the same. The bolt is fitted, at its top, with a thread, the core diameter of which is at least 30 as large as the bolt shank, said bolt being enclosed by a nut of about the same height 35 as the thread, by which the bolt is held 40 protected against damage during running.

In the drawing, a form of embodiment of 45 the invention is illustrated by way of example. Fig. 1 is a section of the beam 50 through the recess receiving the spring. Fig. 2 is a side elevation of the beam with the 55 spring support. Fig. 3 is a plan view of the beam at the recess. Figs. 4 and 5 are 60 side elevation and plan view, respectively, 65 of the lower washer.

Referring to the drawing, the beam 3, 70 through the intermediation of a spring 4, carries the bogie frame 5. The spring 4 is placed in a suitably cylindrical recess 6 in 75 the beam 3 and bears with its lower end on the bottom of the recess. This bottom may be fixed, or it may consist of a removable washer 7. The spring 4 bears at its top 80 on a washer 8, abutting against a bracket 1 85 fastened to the bogie frame. When using a removable bottom washer 7 (a through-going opening in the beam), the washer 7 is suitably provided, at its edge, with recesses 9 corresponding to shoulders 10 in the opening 95 of the beam, thus providing a bayonet-lock 100 for the washer 7. Furthermore, this washer 7 can suitably be provided with downward projections 11 (Fig. 4) fitting in recesses 13 in the shoulders 10 in the opening of the beam, said shoulders forming supporting edges preventing unintentional turning of the washer. The washers 7 and 8 are pro-

vided with central holes. By this means the 55 spring can be compressed by screwing the washers towards each other by means of a screw 12, the mounting being thus exceedingly simple and convenient, since the spring, after having been compressed, can be inserted and removed with the washers as a unit.

According to the invention, the bottom of 60 the recess, or the washer 7, is provided with a projecting sleeve 15, serving to receive the bolt head 14 and having such a length as to effectively embrace the bolt head at any time, when it is in action. By this means, the 65 advantage is gained that the bolt head will never pass beneath the bottom edge of the beam. Moreover, the bolt need not be removed from the bogie during running.

The bolt 12 is fitted, at its top, with a 70 thread, the core diameter of which is at least as large as the bolt shank, said bolt being enclosed by a nut 16 of about the same height 75 as the thread, whereby the same will be securely protected against damage during running.

In compressing the spring for dismounting the parts, the nut 16 is turned so that the bolt 12 is raised until the bolt head 14 bears on the inner top surface of the projecting 80 sleeve 15. By this operation, the nut 16 is screwed down over the bolt shank, which is made possible by the core diameter of the threaded part being at least as large as the bolt shank. The bolt is prevented from 85 turning with the nut, the portion 17 of the bolt shank next to the bolt head 14 being square and formed so as to fit in a corresponding square hole 18 in the upper bottom of the sleeve. When further tightening 90 the nut, the spring 4 will be compressed between the washers 7 and 8 and, thereby, unloaded, whereby it becomes free and can 95 be removed from the bogie.

We claim:

1. A bogie suspension device for vehicles, 100 in which the load is transmitted by springs to a beam, supported by the journal boxes, the springs being placed in vertical recesses in the beams and compressible by means of a bolt, characterized by the respective bottoms of the recesses being provided with a projecting sleeve serving to receive the bolt head and having such a length as to effectively em-

brace the bolt head in every position of the same.

2. A bogie suspension device according to claim 1, characterized by the bolt being provided, at its top, with threads, the core diameter of which is at least as large as the bolt shank, said bolt being provided with a

nut of about the same height as the threaded part, substantially as and for the purpose set forth.

In testimony whereof we have signed our names.

CARL ALFRED SVENSSON.
THEODOR COLLIN.
